Inventor:
George P. Bosworth,
by Emery, Booth, James, and Vassay, Attys.

UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

KNITTED GLOVE AND METHOD OF MAKING THE SAME.

Application filed May 26, 1919. Serial No. 299,789.

To all whom it may concern:

Be it known that I, GEORGE P. BOSWORTH, a citizen of the United States, and a resident of Central Falls, in the county of Providence and State of Rhode Island, have invented an Improvement in Knitted Gloves and Methods of Making the Same, of which the following description, in connection with the accompanying drawings, is a specification, like characters on the drawings representing like parts.

This invention relates to knitted gloves and to the method of making the same, and is an improvement over the gloves disclosed in my co-pending applications, Serial No. 299,788, filed May 26, 1919; Serial No. 298,457, filed May 20, 1919, and Serial No. 298,458 filed May 20, 1919.

The invention has for its object to provide an economical, machine knitted glove, suitably shaped so as nicely to conform to the wrist, hand and fingers of the wearer thereof.

Another object of the invention is to provide a glove particularly adapted to be knitted upon an automatic, circular knitting machine, either as a right-hand or a left-hand glove without material alteration or adjustment of such machine.

In order that the principles of the invention may readily be understood, I have in the accompanying drawings disclosed merely for illustrative purposes certain embodiments, wherein—

Fig. 1 is a perspective view of a finished glove knitted in accordance with my invention;

Fig. 2 is a perspective view of one form of glove blank;

Fig. 3 is a detailed rear view of the wrist of the glove wherein additional means of fashioning are shown;

Fig. 4 is a detailed view, similar to Fig. 3, illustrating the sides of the interruption at the back of the wrist tapering more gradually than in the form shown in Fig. 3.

In the drawings, referring particularly to Figs. 1 and 2, I have illustrated a glove having a wrist 1, herein provided with a wrist opening 2 extending longitudinally of the glove particularly the entire wrist portion thereof and arranged at the front of said glove, the edges 3 and 4 of said opening being suitably seamed or over cast as at 3'

and 4' to prevent ravelling or fraying of said edges.

The wrist 1 is here shown as of relatively small diameter adjacent the end 5, but it is gradually widened or suitably shaped at certain portions thereof to conform to the 60 wrist of the wearer.

The larger end of said wrist is herein knitted integral with the hand of the glove, which hand includes a rotatably knitted seamless tubular web 7 and a reciprocatingly 65 knitted strip 14 of double width and longitudinally doubled along the little or fourth finger side of the glove, so as to bring the two edges 15 and 16 thereof together at the thumb side of the hand where they are 70 stitched together.

The tubular web 7 extends from the end 8 of the wrist opening 2 to the base 9 of the thumb 10, which thumb herein consists of a double-width strip longitudinally doubled 75 along its outer side to bring its edges 17 and 18 at the inside of the thumb and next to the edges 15 and 16 of said hand strip, which edges are as continuations of said edges 17 and 18.

As herein represented the glove has individual finger coverings 19, 20, 21 and 22, indicating the first, second, third and fourth fingers respectively, and these fingers are separated from each other by gussets *a*, *b* 85 and *c* formed in and by the knitting operations, between the first and second, second and third, and the third and fourth fingers respectively.

There are numerous ways by which a 90 glove embodying the features hereinbefore described, may be knitted, that is, it would be within the broad scope and purpose of the invention to knit the glove either by hand or upon various types of machines, 95 but more particularly upon a machine similar in many respects to that disclosed in my co-pending application Serial No. 263,284 filed November 20, 1918. Furthermore, knitting of the glove may begin at 100 any desired point, but herein it is begun at the end 5 of the wrist and when knitted by machine upon substantially the full complement of needles, with the exception of one or more needles that may be withdrawn 105 from action for a certain number of courses, (referring more particularly to the form of blank shown in Fig. 2).

These needles are withdrawn at the front of the wrist 1 of said glove so as to provide an interruption in the circular continuity of the wales or loops, corresponding to the 5 space of one or more wales, according to the number of needles withdrawn. The effect of withholding said needles from action is to produce floating yarns 6 which span the interruption in the series of loops and indicate 10 the line of the wrist opening subsequently to be formed by severing said floating yarns, and thereby separating the two edges of the wrist.

The number of courses that are knitted 15 while certain of the needles are withdrawn will vary according to the size of glove, length of wrist, or length of wrist opening desired. In the present case the length of opening substantially coincides with the 20 length of the wrist, and upon the completion thereof, the needles that have been withheld from operation are restored and knitting continues rotatably, as before, and upon the full complement of needles to form 25 the tubular, seamless section 7 of the hand, this section beginning at the point 8 indicating the terminal point of the wrist opening 2, and continuing to the base line 9 of the thumb 10.

30 The strips 10 and 14 are preferably produced by reciprocating knitting in order to provide selvages at opposite edges thereof, and may be knitted simultaneously by employing separate sets of knitting cams and 35 separate yarn guides, or they may be produced in sequence, each strip being knitted integral with and as a continuation of the tubular hand strip 7.

Having completed the knitting of the 40 thumb and hand portions of the glove, the finger coverings may next be knitted, and although individual finger pockets have been shown, it is distinctly to be understood that the invention herein is not limited to 45 such, but obviously may include mittens wherein a single pocket is provided for all of the fingers, or it may include a glove mitten in which case the thumb and first finger may be contained in separate pockets, 50 and the second, third and fourth fingers in a single pocket.

When the covering is to include individual finger pockets, as herein shown, knitting will proceed upon predetermined or selected 55 groups of needles to form in the desired sequence the strips constituting said pockets. Assuming, however, that knitting is to proceed upon a certain selected group of needles, to effect the formation of the little 60 finger pocket 22, the remaining needles of the series will be withdrawn from action and knitting will proceed reciprocatingly and integral with the strip 14 to form a double width strip 23 which has oppositely sel- 65 vaged edges 24 and 25. This strip will be,

when completed, substantially the length of the fourth finger of the hand, and will be doubled longitudinally midway of its width, so as to present the edges 24 and 25 at the inside of the finger, the outer edge of said 70 finger covering being seamless as in the case of the strip 14 and tubular hand covering 7 of said glove.

Upon completion of the strip 23, one or more other strips may be formed upon 75 selected groups of needles, for instance the front strip 26 of the third finger 21 may be knitted upon a group including a portion of the needles employed in knitting the strip 23, so as to produce an overlapping of said 80 strip with said strip 23 as at 27, for the purpose of forming the gusset c. It is, however, within the province of this invention to effect the knitting simultaneously of the front strip 26 and the back strip 28 of said 85 third finger, and when such is accomplished the necessary needles for said group 28 will be selected in any suitable manner, and these will include portions of the needles employed in knitting the strip 23, so that upon 90 completion of the third finger strips the back strip 28, as well as said front strip 26, will overlap the edges of the fourth finger strip.

In the proper sequence the remaining 95 finger strips may be produced, for instance, the front strip 29 and the back strip 30 of the second finger covering will be formed upon selected groups of needles including portions of the needles employed in knitting 100 the strips 26 and 28, so that there will be an overlapping at 31 of said second and third finger strips to form the gusset b, and following the completion of the strips for the second finger, the front and back strips 32 105 and 33 may be knitted upon selected groups of needles, including portions of the needles used in knitting the strips 29 and 30, thereby by forming strips which overlap at 34 the strips of the second finger, and forming 110 the gusset a between the first and second fingers.

Upon completion of the several strips constituting the finger covering of the glove, the glove may then be removed from the machine and completed by stitching together 115 the various edges of the finger, hand and thumb coverings, all of which edges when produced by reciprocating knitting, as in the present case, will be selvaged edges, and 120 when stitched together will form a seam extending across the tip of the thumb and down the inside of the thumb as at 35 to the base 9 thereof, uniting at this point with a seam 36 formed by the uniting of the 125 edges 15 and 16 of the hand strip 14 and the outer edges of the first finger strips 32 and 33. This seam also continues across the tip of the first finger 19 and down the inside of said first finger to the gusset a, forming 130

ing the seam 37. The strips 29 and 30 of the second finger are stitched together from the gusset *a* upwardly to form the seam 38, which extends across the tip of said second finger and down the opposite side thereof to the gusset *b*. The opposite edges of the fourth finger strips are likewise stitched together from the gusset *b*, across the tip and down the opposite side to the 10 gusset *c*, thus forming a continuous seam 39. The edges 24 and 25 of the fourth finger strip are likewise stitched together from said gusset *c* to form a seam 40 extending therefrom along the inside of the fourth finger 15 and across the tip thereof, thus completing the formation of the thumb and finger coverings of the glove.

Where the hand portion of the glove is formed upon the full complement of the 20 needles and such set of needles is of a size sufficient to include the needles of the thumb in addition to those necessary to produce the hand strip 14, it will be obvious that a tubular web so formed, although being of a 25 suitable size for the hand adjacent to the base of the thumb, will be too large for the wrist. It is therefore desirable that the wrist of the glove formed in this manner be suitably shaped or fashioned in order that it 30 may fit the wrist of the wearer, and to effect this result in the form shown in Fig. 2 the loops of the fabric formed during the knitting of the wrist are herein knitted smaller or shorter than are the loops constituting the tubular fabric 7, and may be 35 effected by using the same kind of yarn as employed in forming said hand, but by varying the relation of the edge of the needle cylinder with respect to the knitting cams, 40 or within the scope and purpose of the invention a lighter yarn may be employed, thus accomplishing practically the same result as would be accomplished by varying the length of the loops thereof. Furthermore, 45 it is obvious that the yarn composing the wrist may contrast both in number, quality and color with the yarn from which the hand and fingers of the glove are produced.

50 There are, however, numerous other methods of effecting the reduction in the diameter or size of the wrist with respect to said hand portion 7, and in properly shaping the wrist. Such variations may be 55 accomplished either during the knitting thereof, or the wrist may be of such a formation that the fastening of the two edges of the wrist together upon the hand of the wearer will result in effecting the necessary 60 reduction in size thereof.

I have, therefore, in Fig. 3, illustrated what may be and herein preferably is a rear view of the wrist wherein the front portion is formed as shown in Fig. 2, that is, 65 with an interruption or gap 41 produced

during the knitting by withdrawing one or more needles and forming floating yarns or elongated sinker wales 42, which span the gap between opposite edges of said opening. It will, however, be obvious that the elongated sinker wales may be produced in other ways than by withdrawing a needle from action during the entire knitting of the wrist; for instance, said wrist may be knitted upon the full complement of needles and 70 at the point 8 in the wrist the loop upon one of the needles may be cast off and such a needle be prevented from taking a new loop, with the result that all of the loops previously formed upon said needles will 75 ravel back and effect the formation of a so-called drop stitch, the floating yarns 42 being subsequently removed or severed and the edges of the fabric suitably treated to prevent the fraying thereof. To further reduce the size of the tube constituting said 80 wrist, I have herein illustrated a V shaped interruption 43 at the back of the glove, which opening may be substantially equal in length to the front opening 41, and may be 85 formed by starting the knitting upon a number of needles considerably less than the whole number of the series, and in gradually throwing such needles into action until all are restored. In other words, the wrist is 90 fashioned by gradually adding needles to the series during the rotary knitting, thus forming floating yarns spanning the V-shaped gap at the back of the groove, which 95 yarns gradually decrease in length as the 100 knitting approaches the juncture of the wrist with the hand portion of the glove to compensate for the adding or restoration of needles. These floating yarns are subsequently severed from the wrist, and the edges 105 of the fabric at the back of said glove united by stitching or seaming in any suitable manner, thus materially reducing the size of the 110 wrist and properly fashioning the same to fit the wrist and adjacent portions of the hand.

In Fig. 4 I have illustrated a portion of a glove blank like that in Fig. 3 wherein a V-shaped interruption 44 is shown spanned by floating yarn 45, said V-shaped interruption being more gradual than the interruption 43, and preferably starting at the end 46 of the wrist rather than farther up the wrist portion as shown in Fig. 3 where the fashioned portion is confined immediately adjacent to the juncture of the wrist and hand portion of the glove, and when the blank is to be completed, the elongated or floating yarns 45 are severed and the edges thereof treated in any desired manner 115 to prevent ravelling or fraying thereof, the 120 fashioning of the edges of said wrist being sufficient when the edges thereof are fastened together to produce a smooth fitting 125 wrist.

In each of the various forms hereinbefore described suitable fastening means, such as ordinarily used in the fastening of gloves, is shown at 51 to retain the edges of the wrist 5 in overlapped relation while being worn.

A glove constructed in accordance with the manner hereinbefore described will, in so far as the hand, thumb and finger portions thereof are concerned, have substantially co-extensive front and back areas whereby the formation of the glove upon a machine will necessitate no changing or adjusting of the machine to produce a pair of gloves, that is, right and left gloves, but 10 when the wrist openings or fashioning of the wrist takes place suitable means may be provided upon the machine for automatically changing the same to produce such openings in either face of the glove, and such automatic changing devices may be arranged so as alternately to produce right and left gloves, or a number of right-hand gloves may be produced in succession upon the machine, and then the machine operate to produce an equal number of left-hand gloves. Either method, however, may be effected 20 without manual or complicated alterations in order to produce the desired result.

Having thus described certain illustrated 30 embodiments of my invention, I desire it to be understood that although specific terms are employed they are used in a generic and descriptive sense and not for purposes of limitation, the scope of the invention being 35 set forth in the following claims:

Claims.

1. A knitted glove blank having a tubularly knitted wrist provided with an interruption extending longitudinally thereof, 40 and formed in and by the knitting operations.

2. A knitted glove blank having a wrist including interrupted circular series of loops connected by floating yarns.

45 3. A knitted glove having a wrist provided with a wrist opening formed in and by the knitting operations, an integrally knitted hand covering including a tubular seamless portion and a selvaged strip, and digit coverings formed integral with said hand.

50 4. A knitted glove blank having a tubular wrist consisting of interrupted circular series of loops, the interruption of said series occurring at the front of said wrist, floating 55 yarns spanning said interruption, a hand partly tubular and partly a selvaged strip and digit coverings knitted integral with said hand.

60 5. A knitted glove having a fashioned wrist provided with an opening at the front thereof, a hand including a seamless tubular portion and a selvaged strip portion, and thumb and finger coverings forming together with said hand substantially coextensive 65 front and back areas of said glove.

6. A knitted glove having a wrist provided with an opening formed in and by the knitting operations longitudinally and at the front of said glove and a hand-portion constituting an integral continuation of said 70 wrist.

7. A knitted glove having a wrist provided with a longitudinal opening, a hand including a tubular portion and an oppositely selvaged portion, a thumb strip knitted as an integral continuation of the rotatably knitted portion of said hand, and finger coverings constituting integral continuations of the oppositely selvaged portion of said hand. 75

8. A knitted glove blank having tubular wrist and hand coverings of integrally united but of different diameters, said wrist consisting of interrupted circular series of loops, opposite ends of said series of loops 85 being connected together by floating yarns.

9. A knitted glove blank having tubular wrist and hand coverings, said coverings having a longitudinal interruption in the circular continuity of the wales thereof corresponding with the space of one wale, said interruption being spanned by floating yarns. 90

10. A knitted glove blank having tubular wrist and hand coverings provided with an interruption in the circular continuity of the wales thereof, said interruption extending from the end of said wrist longitudinally of a portion of said glove, and floating yarns spanning said interruption. 95

11. A knitted glove having integrally knitted 100 wrist and hand coverings provided with a gap in the wales formed longitudinally and at the front of said glove, the loops composing said wrist contrasting in size with those of said hand.

12. A knitted glove blank having a hand covering including a seamless tubular web, a shaped wrist knitted integral with said hand, said wrist also having one wale of loops omitted to indicate the line of a wrist 110 opening, and floating yarns spanning the gap produced by the omission of said wale. 105

13. That method of knitting a glove which consists in knitting rotatably upon an incomplete circular series of needles to 115 form a wrist having a longitudinal interruption at the front thereof, in knitting upon the complete series of needles a tubular web constituting a part of the hand covering, in knitting a thumb strip upon a 120 selected group of said needles, in knitting a strip of fabric constituting a portion of the hand covering, upon the remaining needles of said series, and in knitting finger coverings upon the latter series of needles, 125 integral with said hand.

14. That method of knitting a glove which consists in starting to knit rotatably upon a reduced number of needles to form a wrist having an interruption in the cir- 130

- cular continuity of wales, in knitting a tubular hand portion upon the complete set of needles, in knitting a double-width thumb strip upon a selected group of said needles, in knitting an oppositely selvaged hand strip upon the remainder of said needles and in knitting upon selected groups of the latter needles, a plurality of finger coverings. 5
- 10 15. That method of knitting a glove which consists in starting to knit rotatably upon a reduced number of needles to form a wrist having an interruption in the circular continuity of wales, in gradually varying the length of the loops to shape said wrist, in knitting a tubular hand portion upon the complete set of needles, in knitting a hand strip of fabric integral with said tubular hand portion, in knitting a 20 double-width thumb strip integral with said hand, and in knitting a plurality of finger covering strips integral with said hand strip. 25
16. That method of knitting a glove which, consists in knitting rotatably upon an incomplete circular series of needles and in varying the length of the loops during said knitting to form a shaped tubular wrist having a longitudinal interruption 30 corresponding to the space of one wale, and spanned by floating yarns, in knitting rotatably upon all of the needles to form a tubular hand covering section, in knitting reciprocatingly upon a selected group of 35 said needles to form a double-width selvaged thumb strip, in knitting reciprocatingly upon the remainder of said needles to form a continuation of said tubular hand, and in knitting upon selected groups of the 40 latter needles a plurality of overlapping front and back finger strips. 45
17. A knitted glove having a hand covering including a seamless tubular web and a longitudinally doubled, selvaged strip, a longitudinally doubled, selvaged thumb strip knitted as a continuation of said tubular web, and a plurality of overlapping finger coverings constituting continuations of each of the folds of said hand strip. 50
18. A knitted glove having a hand including a seamless tubular web and an integral double-width strip, the edges of said strip being stitched together along the thumb side of the glove, a double-width
- thumb strip knitted integral with said tubular web, the edges of said thumb strip being stitched together and forming a seam uniting with the seam of said hand strip and extending along the inside of said thumb and across the tip thereof, a plurality of finger coverings knitted integral with said hand strip, and gussets formed between said several fingers in and by the knitting operations. 55
19. In the method of knitting a glove blank, that step which comprises knitting a wrist by a series of circular courses, wherein the continuity of the loops is interrupted by floating yarns. 60
20. That method of knitting a glove comprising knitting a wrist portion having a wrist opening formed in and by the knitting operation, knitting integrally with said wrist portion a hand covering having a tubular, seamless portion, and a flat portion, and knitting digit coverings integral with the hand portion. 70
21. That method of knitting a glove blank comprising knitting a tubular wrist having interruptions in the circular continuity of the loop courses at the front of said wrist by floating yarns, spanning said interruptions and knitting a hand as a continuation of said wrist partly by tubular knitting and partly by the formation of a selvaged strip and knitting digit coverings integral with said hand. 80
22. That method of knitting a glove comprising knitting a wrist having a longitudinally extending opening formed in and by the knitting operation at the front of the glove and constituting an interruption in the continuity of the courses forming the wrist, and knitting a hand portion constituting an integral continuation of said wrist. 90
23. That method of knitting a glove comprising forming a tubular wrist and automatically shaping the same during the formation thereof and during the formation thereof forming an opening longitudinally of the wrist at the front by interrupting the continuity of the courses of loops forming a hand integrally knitted with the wrist and forming thumb and finger portions. 100
- In testimony whereof I have signed my name to this specification. 105
- GEORGE P. BOSWORTH.
